United States Patent Office

Des. 202,883
Patented Nov. 16, 1965

202,883

TRACTOR

William H. Armstrong and Jack L. Ponkey, both of Birmingham, Mich., assignors to Yard-Man, Inc., Jackson, Mich., a corporation of Michigan

Filed May 25, 1964, Ser. No. 80,118

Term of patent 14 years

(Cl. D14—3)

FIG. 2

-FIG. 5

FIG. 1 is a front and side perspective view of a tractor showing our new design,

FIG. 2 is an elevational view of the left side of the tractor, the right side being similar thereto,

FIG. 3 is a plan view,

FIG. 4 is a front elevational view, and

FIG. 5 is a rear elevational view.

The dominant features of the design reside in the portions shown in full lines.

We claim:

The ornamental design for tractor, as shown and described.
